UNITED STATES PATENT OFFICE.

WILLIAM ALEN GENTRY, OF TRENTON, GEORGIA, ASSIGNOR OF ONE-HALF
TO W. G. MORRISON, OF SAME PLACE.

RATCHET MINING-DRILL.

SPECIFICATION forming part of Letters Patent No. 393,895, dated December 4, 1888.

Application filed September 6, 1887. Serial No. 248,991. (No model.)

To all whom it may concern:

Be it known that I, WILLIAM ALEN GENTRY, of Trenton, in the county of Dade and State of Georgia, have invented a new and useful 5 Improvement in Ratchet Mining-Drills, of which the following is a specification.

My invention is a hand-drill which is particularly adapted for use in confined spaces.

The invention is embodied in the construction and arrangement of parts hereinafter described and claimed.

Figure 1 is a side elevation (part of the tube being in section) of the drilling apparatus as arranged when in use with a short 15 drill proper. Fig. 2 is a side elevation of the apparatus in use with a longer drill proper, the feed-screw being reversed to begin boring anew. Fig. 3 is a cross-section on line $y-y$, Fig. 1. Fig. 4 is a cross-section on line $x-x$, Fig. 1. Fig. 5 is a perspective view of the polygonal nut.

The tubular stock or barrel A of the drill has a socket at one end to receive the drill B and a socket, A^2 , at the other end to receive 25 the polygonal nut C, through which the screw D works. The reversible nut C has a central flange, C' , and either of its polygonal ends C^2 C^3 will snugly fit the correspondingly-formed socket A^2 of the barrel.

30 The feed-screw D is threaded from end to end, and has at each end a conical centering-point, d , a collar, d' , which snugly fits the interior of the barrel A, and a hole to receive the pin d^3 , for holding the feed-screw stationary while the barrel revolves upon it. The collars d' , above described, together with the nut C, will hold and guide the feed-screw steadily within the tubular stock and prevent wabbling.

40 A ratchet-wheel, F, is securely keyed to the stock A, and collars G, having projecting ears g , are fitted to turn freely upon said stock against the sides of the said ratchet-wheel, and are secured by bolts $g' g'$ to the opposite 45 sides and end of a hand-lever, H. The hand-lever H carries a spring-pawl, I, upon the end h , located squarely opposite the faces of the ratchet-teeth, and is bent at its middle portion, h' , and its end h^2 , to provide a handle,

which will be located squarely opposite the 50 ratchet-wheel F, and thus relieve the drill, the stock, and the feed-screw of unequal or twisting strains which would tend to lessen the accuracy of the work.

In Figs. 1 and 2 the apparatus is shown 55 in operation with drills proper of different lengths and arranged horizontally, the feed-screw D being supported at its outer end on the step or sleeve E, which is adjustably clamped on an extensible post that is secured 60 vertically, in the usual way, between the roof and floor of the "gallery." The pin d^3 is in contact with the arm of sleeve E and prevents rotation of the screw. In Fig. 1 the short drill proper is shown as having entered 65 the breast nearly its length, and consequently the nut C has been worked along the feed-screw D nearly to its outer end, and the screw has also necessarily entered the tube A to a corresponding length. In order to bore still 70 deeper into the breast, it is necessary to remove the said short drill proper and substitute a longer one, as shown in Fig. 2. At the same time the feed-screw D is removed from the tube A and reversed, so that its outer 75 end and the nut C enter the tube, and its inner end is centered and supported on the adjustable sleeve E, as before, all as shown in said Fig. 2. Thus the apparatus is prepared for boring farther, and such operation may be 80 continued until the longer drill proper shall have entered the breast to its full length, when the nut C will have worked along the feed-screw nearly to the outer head of the latter, as before.

85 The reversibility of the screw and nut is therefore very important in practical operation, and has the further advantage of causing the threads of the screw and nut to wear equally on each side.

90 I claim as my invention and desire to secure by Letters Patent—

1. The combination of the reversible nut C, having the central peripheral flange, C' , and similar polygonal ends, C^2 C^3 , with the feed-screw D, working through said nut, and the tubular drill-stock A, having the socket A^2 at one end adapted to receive either end of

the nut, and the ratchet, pawl, and lever for rotating the drill-stock, as shown and described.

2. The combination of the pin d^3 , the sleeve 5 E, having an arm against which said pin bears, with the post, on which the sleeve is adjustably secured, the feed-screw having a

hole in each end to receive said pin, the nut C, drill-stock A, and ratchet-lever mechanism, as shown and described.

WILLIAM ALEN GENTRY.
